H. C. BASCOM.
COOKING STOVE.

No. 15,679.

Patented Jan. 6, 1885.

UNITED STATES PATENT OFFICE.

H. CLAY BASCOM, OF TROY, NEW YORK.

DESIGN FOR A COOKING-STOVE.

SPECIFICATION forming part of Design No. 15,679, dated January 6, 1885.

Application filed October 20, 1884. Term of patent 7 years.

To all whom it may concern:

Be it known that I, H. CLAY BASCOM, a citizen of the United States, residing in the city of Troy, in the county of Rensselaer and 5 State of New York, have invented and produced a new and original Design for a Cooking-Stove, of which the following is a specification, reference being had to the accompanying 10 engraving of a cooking-stove having said design.

This design relates to several new and distinctive parts which go to make up the whole design, as hereinafter specified. One part is the 15 ornamentation of the rectangular doors A B C D and panel E, consisting of the four compound corner portions b, each in the general shape of a right-angled triangle with truncate corners and having beaded sides, the fan-form corner ornament c and floral ornament d, and 20 the floret ornaments e between the said corner portions. Another part is the shape and ornamentation of the rectangular door A, embracing its outer border-molding, the corner 25 ornamentations b, shown on said door, and the raised plate ornament F, of rhombic form, and having the middle longitudinal name-band, f, the sectors and triangles g on each obtuse corner, and the triangles and hexangular figure h on each acute end. Another part is the 30 shape and ornamentation of the rectangular doors B, embracing the outer border-molding, the corner ornaments b, shown on said doors, and the raised plate ornament G, of rhombic form, and having the sector-like and 35 triangular figures i on the obtuse corners, the figures j at the acute ends, and the incut ornaments k in the flat face of the plate. Another part is the shape and ornamentation of the raised rectangular panel C, D, or E, embracing the outer border-molding and corner 40 ornaments b, shown on said panel, and the raised plate ornament H, of a general quadrilateral form, with the triangular and sector-shaped figures l at two opposite corners, the 45 three angular figures m at the two other corners, and the central rhombic figure, n, in the flat face. Another part relates to the shape and ornamentation of the rear extension-plate, I, having the ornamented panel E, re- 50 versely curved, and angular lower border, o,

and the compound ornament p. Another part is the shape and ornamentation of the end door, J, the same embracing the upper raised rectangular flat-faced panel, q, having the three quadrilateral mica lights r, with molded 55 truncate corners, and the intermediate ornaments r', the inclined panel part s, having the ornament t, and the flat-faced lower portion, u, having the row of six oblong apertures, v, with rectangular bottoms and contracted 60 pointed tops, and the intermediate ornaments w. Another part is the ornamentation of the lower end plate, K, consisting of the rectangular panel x, having the compound scroll and floret middle ornament, y, and the four corner 65 ornaments z, as shown.

The whole design embraces the shape and ornamentation of the top, the front, including the doors A B C D, panel-plates F G H, and extension I, the end, including its hearth 70 and the parts J and K, and the upper and lower bottom plates, L and M, substantially as shown.

I claim as new—

1. In a design for a stove, the ornamentation of the rectangular doors and panel A B C D E, embracing the parts b, c, d, and e, as 75 shown and described.

2. In a design for a stove, the shape and ornamentation of the rectangular door A, embracing its border-molding, corner ornaments b, and raised plate ornament F, of rhombic 80 form, and having the ornamental parts f g h, as shown and described.

3. In a design for a stove, the shape and ornamentation of the rectangular doors B, embracing the border-molding, corner ornaments b on said doors, and the raised plate ornament G, of rhombic form, and having the ornamental 85 figures i j k, as shown and described. 90

4. In a design for a stove, the shape and ornamentation of the rectangular panels C, D, or E, embracing the border-molding, corner ornaments b, and the angular plate ornament H, having the ornamental figures l m n, as 95 shown and described.

5. In a design for a stove, the shape and ornamentation of the rear extension-plate, I, embracing the parts E, o, and p, substantially as set forth. 100

6. In a design for a stove, the shape and ornamentation of the door J, embracing the parts q r r', s t, and u v w, as shown and described.

7. In a design for a stove, the ornamentation of the lower end plate, K, consisting of the parts x y z, as shown and described.

8. The design for a stove, embracing the top, the front, including the parts A B C D F G H I, the end, including its hearth and the parts J K, and the bottom plates, L M,

shaped and ornamented substantially as set forth.

In testimony whereof I hereunto set my hand, in the presence of two subscribing witnesses, this 17th day of October, 1884.

H. CLAY BASCOM.

Witnesses:

CHARLES H. BENEDICT,
JAMES A. GILMAN.
